UNITED STATES PATENT OFFICE.

DEMETRIUS A. KEMP, OF NEW YORK, N. Y., ASSIGNOR TO KEMP & BEATLEY, INC., OF NEW YORK, N. Y., A CORPORATION OF NEW YORK.

DESIGN FOR A TABLECLOTH.

Application filed October 12, 1926. Serial No. 19,307. Term of patent 3½ years.

To all whom it may concern:

Be it known that I, DEMETRIUS A. KEMP, a citizen of the United States, residing in the city, county, and State of New York, have invented a new, original, and ornamental Design for a Tablecloth, of which the following is a specification, reference being had to the accompanying drawings, forming part thereof.

Drawings:

The figure is a top view of a table cloth showing my ornamental design.

I claim:

The ornamental design for a tablecloth as shown.

DEMETRIUS A. KEMP.
